THERMOSTAT

Waldo A. Saul, Lexington, Mass., assignor to Metals & Controls Corporation, Attleboro, Mass., a corporation of Massachusetts

Application September 25, 1940, Serial No. 358,199

18 Claims. (Cl. 200—113)

This invention relates to thermostats, and more particularly to thermostats containing composite thermostatic elements wound in the form of a helix such as shown and described in Parsons United States Patent 2,121,259, dated June 21, 1938.

Among the objects of the invention may be noted the provision of a simple and compact thermostat embodying a thermostatic element such as shown in said Parsons patent, which operates automatically but with manual re-setting; the provision of such a thermostat which may be made sensitive to rates of change of temperature; the provision of such a thermostat which in certain useful respects, is not affected by ambient temperature changes; the provision of a thermostat of the class described which operates with a snap action, thereby eliminating or decreasing arcing between contacts; and the provision of a thermostat of the class described which is in one form trip-free of the re-setting mechanism. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which are illustrated several exemplary embodiments of the invention,

Fig. 1 is a plan view of one type of thermostat made in accordance with the present invention;

Fig. 2 is a front elevation of the Fig. 1 thermostat;

Fig. 3 is a cross-section taken along the line 3—3 of Fig. 1;

Fig. 4 is a left end elevation of the Fig. 1 thermostat;

Fig. 5 is a section taken along the line 5—5 of Fig. 2;

Fig. 6 is a section taken along the line 6—6 in Fig. 2;

Fig. 7 is a section taken along the line 7—7 of Fig. 2;

Fig. 8 is a section taken along the line 8—8 in Fig. 2;

Fig. 9 is a plan view of another type of thermostat embodying the invention;

Fig. 10 is a front elevation of the Fig. 9 thermostat;

Fig. 11 is a section taken along the line 11—11 in Fig. 9;

Fig. 12 is a rear elevation of the Fig. 9 thermostat;

Fig. 13 is a left end elevation of the Fig. 9 thermostat;

Fig. 14 is a section taken along the line 14—14 in Fig. 10;

Fig. 15 is a section taken along the line 15—15 in Fig. 10;

Fig. 16 is a section taken along the line 16—16 in Fig. 10; and,

Fig. 17 is a section similar to Fig. 11, but showing a still different embodiment of the invention.

Similar reference characters indicate corresponding parts throughout the several views of the drawings.

The present invention refers to composite thermostatic elements of the type shown and described in said Parsons Patent No. 2,121,259, and to thermostats embodying these composite elements. An element of this type may be made by first winding a narrow strip of composite thermostatic metal, such as bimetal, into a helical form having a relatively small diameter. This minor helix is then wound as a second or major helical form of relatively large diameter, thus forming a compound or double helical thermostatic element, or a peripherally continuous, operating member, as described in said Parsons Patent 2,121,259. The composite metal, or bimetal helix, or spring, so formed, will expand or contract lengthwise with change of temperature. The amount of movement for a given temperature change is controlled by the relation between the various dimensions of the element, and the direction of movement is controlled by the direction of the winding of the two helices and the relative position of the high and low expansion sides of the bimetal.

Referring to the drawings, Fig. 1 shows a thermostat 1, embodying helices 2 and 3 of the type described above. The end 4 of thermostatic element 2 is attached to a member 5, provided with a terminal screw 6. The other end 7 of thermostatic element 2 is attached to member 8, for example, by welding, as shown at 9 (see Fig. 1). Member 8 is held in desired position on shaft 10 by screw 11. Shaft 10, it will be noted, extends through the center of the helix 2. On one end of shaft 10 is fixed a manual re-setting means, such as the pointer 12. This may be in the form of an off-on switch, such as shown in Fig. 4. The shaft 10, extends not only through the thermostatic element 2, but also through the thermostatic element 3. The two elements are mounted approximately concentrically and separated by insulator 58 as well as by member 8.

Insulator 58 is slidably mounted on shaft 10. Shaft 10 is slidably endwise in its bearings in the base 1, carrying with it the member 8. Member 8 has a projection 13 upon which is mounted a contact button 14. This contact button 14 cooperates with another contact button 15, mounted upon member 16. Member 16 is attached to thermostatic element 3 at 17. Also attached to member 16 at 17 is a non-heating electrical conducting wire 18. Wire 18 is shown mounted axially within the small helix. This wire is connected at its opposite end 19 to member 20. Thermostatic element 3 is also attached to member 20 at 21.

The portion 13 of member 8 is positioned to rest upon a latch 22 when the thermostat is in the Fig. 2 position. This latch is mounted upon a sliding support 91 slotted as at 93 to provide for adjustment under a set screw 95. Adjustment is parallel to the axial movement of shaft 10.

The operation of the device is as follows: Taking Fig. 1 as the primary or starting position of the device, the portion 13 of member 8 is positioned below the latch 22. In this position the thermostatic elements 2 and 3 are substantially free of stress and the contacts 14 and 15 are open. The knob 12 in this position will point to the word "off" as shown in dotted lines in Fig. 4. Manually rotating the setting means 12 to the "on" position shown in Fig. 4, rotates the shaft 10, and thereby imposes stress or torsion upon the thermostatic element 2. Such rotation likewise serves to move the catch portion 13 of the member 8 past the latch 22 so that it springingly rests thereupon, as shown in Fig. 2. This rotation also closes contacts 14 and 15, since element 3 is so positioned that for a part of its motion before portion 13 of member 8 slides up and over the latch 22, contact 14 has met contact 15 to rotate member 3 about its axis and place torsional stress therein. Contacts 14 and 15 are therefore held springingly together by the opposing torsions of the thermostatic helical elements.

Thermostatic elements 2 and 3 are so constructed and positioned in the device, that their tendencies to expand longitudinally for a given change of temperature are in opposite axial directions. Thus an increase in ambient temperature will have substantially no effect upon the longitudinal position of the portion 13 of member 8. The elements in effect buck one another to cancel out movement, that is, the tendency of thermostatic element 2 to expand toward the right in the Fig. 2 position is opposed by the equal tendency of thermostatic element 3 to expand toward the left. Contacts 14 and 15 thereby are retained in one position, and in contact, because of the previous latching and the bucking action.

If a circuit is now established between terminals 6 and 23, the current passes from terminal 6 through member 5, to thermostatic element 2 at 4, thence from thermostatic element 2 to member 8 to contact button 14 to contact button 15 to member 16, and thence through both thermostatic element 3 and non-heating wire 18 to member 20 and terminal 23. Since the thermostatic element 3 is arranged in parallel with non-heating (low resistance) wire 18, passage of the current will have substantially no tendency to cause the thermostatic member 3 to expand. However the current all passes through thermostatic member 2, and thereby tends to cause the member to expand toward the right. Conditions are adjusted so that passage of a safe current

through the circuit is not sufficient to cause the thermostatic element 2 to expand sufficiently to bring the portion 13 of member 8 out of engagement with latch 22. However, the additional expansion caused by a deleteriously high current passing through thermostatic element 2 is sufficient to expand the element sufficiently to cause portion 13 to be moved to the right out of engagement with latch 22. As soon as this occurs, the stress in thermostatic element 2 forces member 8, and its portion 13 carrying contact button 14, downwardly out of engagement with contact button 15, thus breaking the circuit.

Cooling of the device after breaking the circuit will cause the thermostatic element 2 to contract again, pulling the member 8 and its portion 13 to the left. However, there is no tendency from this action to re-introduce the torsional stress into the element 2, and as a result there is no tendency automatically to bring contacts 14 and 15 together to re-establish the circuit. This must be done mechanically by turning the knob 12 to the "on" position, thus bringing the portion 13 of member 8 again on top of the latch 22, and the contact button 14 thereby into engagement with contact button 15.

The device is independent of ambient temperature changes, and operates with a snap action. It is also automatically re-setting to a condition for potential latching.

An alternative embodiment of the invention is shown in Fig. 9. Here a thermostat 24 has mounted thereon a thermostatic element 25, embodying a helix, such as described previously. A shaft 26 passes through the helix, and is rotatably mounted in the thermostat. The end 27 of the shaft projects from the thermostat and has a manual resetting knob 28 mounted thereon. The thermostatic element 25 is mounted at one end 30 on member 29, as shown at 30 (see Fig. 12). On the other end of the thermostatic element 25 is mounted a plate 31. This plate is rotatably mounted on shaft 26, and has a slot 32 adapted to receive key 33, which is rigidly attached to shaft 26. This key 33 normally prevents rotation of the plate 31. Rotation of the entire assembly is prevented in one direction by projecting portion 34, which cooperates with a notch 35, cut in the thermostat assembly mounting. A coil spring 36 attached at opposite ends to the frame of the thermostat 24 and to the plate 31 respectively, operates to oppose any tendency of the plate 31 to move to the right (Figs. 9-11), and maintains the plate 31 in operative association with the key 33 under normal conditions. Spring 36 also operates as a torsion spring to rotate plate 31 counter-clockwise to the Fig. 16 position where it is stopped by notch 35.

Mounted on the thermostat frame are contact terminals 37 and 38. These are arranged to cooperate with movable contact buttons 39 and 40, which are mounted on member 29 by means of cross bar 41. Cross bar 41 is formed of some non-conducting substance. Attached to contact button 40 by means of a pigtail 42 is a non-heating wire 43. The other end of wire 43 is attached to plate 31 at 44, as by screw 45. Terminal 39 is electrically connected to member 29 by wire 46.

Therefore, the circuit established is from terminal 37 through contact button 47 to contact button 39 to wire 46 to member 29 to thermal element 25 to plate 31 to wire 43 through pigtail 42 to movable contact 40 to stationary contact button 48 to terminal 38.

Manual re-setting button 28 mounted on shaft

26 has a projecting portion 49 which moves with knob 28. This projection 49 is positioned to ride over projection 50 attached to the frame of the thermostat. Projection 50 is mounted on flexible plate 51 which in turn is attached by screw 52 to the frame of the thermostat. Plate 51 is preferably made of resilient material, so that if it is desired to manually release the contacts, this may be easily accomplished by pressing upon knob 53 which projects through the thermostat frame assembly, and tends to push member 51 away therefrom, contacting it at 54.

Member 51 preferably has a projection 55 arranged to cooperate with an opening 56 in the thermostat frame assembly. The word "off" may then be conveniently inscribed upon the projecting portion 55, and will show when the thermostat is in the Fig. 13 position. A projecting portion 57 may also be conveniently attached to the member 29, and so positioned that upon rotation of the knob 28 as the projection 49 passes over the projection 50 the projecting portion 57 is interposed between projection 55 and the opening 56 in the thermostat frame assembly. The word "on" is inscribed upon projection 57.

The operation of the device is as follows: When the thermostat is in the Fig. 13 position, so that the word "off" shows, and the projecting portion 49 is to the right of projection 50, the thermostatic element 25 is substantially free of stress. Rotation of the knob 28 turns shaft 26 and thus plate 31. Plate 31 turns (against the restraining force of spring 36) to turn the thermostatic element 25. This turns member 29 with its movable contacts 39 and 40 and brings movable contacts 39 and 40 into engagement with stationary contacts 47 and 48. Member 29 is rotary on shaft 26 so that knob 28 may continue to rotate the shaft after the movable contacts have engaged the stationary contacts. Such further rotation, which puts thermostatic element 25 under torsion, as well as spring 36, is necessary to bring projecting portion 49 past projection 50. Bringing the movable contacts into engagement with the stationary contacts completes a circuit, the current passing in the path described above.

The passage of normal current operates to heat the thermostatic element 25 and cause it to expand toward the right in Fig. 9. This expansion is adjusted, however, so that it is not sufficient to cause the plate 31 to move sufficiently far to the right so that it is free from the key 33. However, upon the passage of a deleteriously high current through thermostatic element 25, the expansion is adjusted to be sufficient to move the plate sufficiently far to the right so that it no longer has the slot 32 therein engaging the key 33. This releases that end of the thermostatic element 25, and allows the stress stored in spring 36 by manual setting of the knob 28 to cause rotation of the member 29 assembly and moves the contacts 39 and 40 out of engagement with contacts 47 and 48, thus breaking the circuit. Projecting portion 34 of plate 31 cooperates with slot 35 in the thermostat frame to prevent the release of more than a part of the stress stored in spring 36. Thus spring 36 is always torsionally stressed in a direction to tend to open the switch. It transmits a large opening movement to the switch through plate 31 and the connected thermostatic element 25 even when the latter is unstressed (after plate 31 has left key 33 and contacts 39 and 40 have left contacts 47 and 48).

Re-setting of the device is accomplished by 75

turning the knob 28 through almost a complete revolution clockwise (Fig. 13), thus bringing the key 33 back into alignment with the slot 32 in plate 31. If the thermostatic element 25 has then cooled sufficiently to contract and bring the plate 31 into engagement with the key 33, the knob 28 may then be further rotated until the portion 49 passes the projection 50 and the device will then operate as before. However, if the thermal element 25 has not cooled sufficiently so that the plate 31 will engage the key 33, the device cannot be re-set and the circuit cannot be reclosed. The device is therefore trip-free or latch-free of the manual re-setting means.

15 From the foregoing description, it will be apparent that the device will not automatically reset itself, nor will the preferred form of Figs. 1-8.

An alternative form of the thermostat shown in Figures 9 to 16 is represented in Fig. 17. The thermostat in this instance has been ambient-compensated; that is, it is not affected by changes in the ambient temperature to which the device may be subjected.

The thermostat shown has two thermostatic elements 70 and 71. Thermostatic element 71 is similar in all respects to thermostatic element 25 in Figures 9 to 16. Thermostatic element 70, however, is wound in the same way as thermostatic element 71 but with the opposite side of the composite metal outward, and as a result, element 70 contracts when heated, while element 71 expands when heated. Elements 70 and 71 are wound so that their tendency to contract and expand respectively upon rise in temperature, is equal; that is, element 71 will expand in a longitudinal direction the same distance that element 70 will contract when both elements are subjected to the same increase in temperature. As a result, changes in ambient temperature have substantially no effect upon plate 31. The contraction of thermostatic element 70 exactly counteracts and balances the expansion of thermostatic element 71, thus leaving plate 31 unaffected.

45 Thermostatic element 71 however, is connected at 20 in series with the current which it is the purpose of the device to control, as thermostatic element 25 was so connected in the embodiment shown in Figures 9 to 16. The heating effect of the current normally passed through the circuit is operative only upon thermostatic element 71, its passage causing the element to expand. This expansion, as in the case of thermostatic element 25, is adjusted so that it is not sufficient to cause the plate 31 to move sufficiently far to the right to be free from the key 33. Upon the passage of a deleteriously high current, however, through thermostatic element 71, the expansion is adjusted to be sufficient to move the thermostatic element 70 and plate 31 sufficiently far to the right so that the slot 32 in plate 31 no longer engages key 33. This releases the fixed end of the thermostatic elements 70 and 71, and allows the stress stored in spring 36 by the manual setting of the knob 28 to rotate the member 29 assembly, thereby moving the contacts 39 and 40 out of engagement with contacts 47 and 48 to break the circuit.

70 It will be understood of course that the adjacent ends of thermostatic elements 70 and 71 are connected together so that the partial release of the torsion in spring 36 will rotate the movable contacts 39 and 40 out of engagement with the stationary contacts 47 and 48. Alternatively, the movable contacts may be mounted upon ther-

mostatic element 70 instead of upon thermostatic element 71. In this case it is not necessary that thermostatic elements 70 and 71 be connected together.

It will be clear of course that the Fig. 1 to 8 method of compensating for ambient temperature change may be applied to the Fig. 9 to 17 embodiments. Thus the plate 31 may be positioned between thermostatic elements 70 and 71. Thermostatic element 70 in this case will be an exact counterpart of thermostatic element 71, and will expand with increase in temperature, just as thermostatic element 71 will do. Spring 36 is preferably located inside thermostatic element 71 and is attached to plate 31 and the frame of the thermostat as before. In this alternative, the two thermostatic elements 70 and 71 will buck one another upon increase in ambient temperature, and there will be substantially no longitudinal movement by either upon such increase in ambient temperature. Only thermostatic element 71 is connected in series with the current, however, so that it only is affected by the current which it is desired to control. A deleterious increase in this current will therefore be sufficient to heat the thermostatic element 71 enough to push plate 31 out of engagement with key 33, and permit spring 36 to carry out the rotating action described previously, thus separating the movable contacts from the stationary contacts.

From the above it will be seen that the motivating thermostatic element of this invention consists of a strip of composite metal extended progressively about a first minor axis to form minor coils around that axis, said minor axis being in turn extended or coiled about a second major axis to form major coils. Such a construction provides a double coil construction providing for large torsional angular strains (to accomplish angular contact action), and also to provide substantial linear axial expansion along the major axis to release the detent or latch. By means of this double coil construction, there is obtained a thermostatic element which has a large axial movement upon temperature change and which has a large torsional movement which can be utilized to close and open contacts without damaging stress being set up in the bimetal.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

What is claimed is:

1. A thermostat comprising a helical coil axially expansible in response to temperature change composed of a strip of composite metal, a stationary contact, a movable contact operable by said coil, means for placing the coil under stress, and a latch for preventing release of said stress before a predetermined temperature is reached.

2. A thermostat comprising two helical thermostatic members in abutment, axially expansible in opposite directions in response to temperature changes and abutting one another to cancel movement when temperature change is ambient to both thermostatic members, the abutment moving when one of the members is heat-

ed independently of the other and means for independently heating one of the members.

3. A thermostat comprising two helical thermostatic members in abutment, axially expansible in opposite directions in response to temperature changes and abutting one another to cancel movement when temperature change is ambient to both thermostatic members, the abutment moving when one of the members is heated independently of the other and means for independently heating one of the members, a second abutment between said members comprising switch contacts normally spaced, manual means for driving one contact against the other by operation of one thermostat whereby one of the thermostatic members is tensioned, a latch for maintaining said tension, said one thermostatic member when sufficiently expanding in response to said independent heating moving the abutted contacts from the latch whereby they open.

4. A thermostat comprising two helical thermostatic members in abutment, axially expansible in opposite directions in response to temperature changes and abutting one another to cancel movement when temperature change is ambient to both thermostatic members, the abutment moving when one of the members is heated independently of the other and means for independently heating one of the members, a second abutment between said members comprising switch contacts normally spaced, manual means for driving one contact against the other by operation of one thermostat whereby one of the thermostatic members is tensioned, a latch for maintaining said tension, said one thermostatic member when sufficiently expanding in response to said independent heating moving the abutted contacts from the latch whereby they open, the sufficiency of said expansion from heating being determined by overheating as distinguished from normal heating.

5. A thermostat comprising two helical thermostatic members in abutment and axially expansible in opposite directions in response to temperature changes and abutting one another to cancel movement when said temperature change is ambient to both thermostatic members, the abutment moving axially when one of the members is heated independently of the other, and means for independently heating said one of the members, a second and torsional abutment between said members comprising switch contacts normally spaced, manual means for driving one contact against the other by torsional operation whereby one of the thermostatic members is tensioned in torsion, a latch for maintaining the torsional tension, said one thermostatic member expanding axially in response to said independent heating to move the torsionally abutted contacts from the latch.

6. A thermostat comprising two helical composite thermostatic members in abutment and axially expansible in opposite directions in response to temperature changes and abutting one another to cancel movement when said temperature changes are ambient to both members, the abutment moving axially when one of the members is heated independently of the other, means for heating said one member independently of the other, a second and torsional abutment between said members comprising switch contacts normally spaced, manual means for driving one contact against the other by torsional operation of said one member whereby both thermostatic members are tensioned, a latch for maintaining

said tension, said one thermostatic member expanding axially in response to excessive local heating to move the torsionally abutted contacts from the latch, said contacts automatically reopening after movement from the latch and remaining clear of the latch until the excessive conditions are disestablished, said latch maintaining the tension during non-excessive local heating of the one thermostatic member.

7. A thermostat comprising a base, helical thermostats having ends in axial abutment, whereby ambient temperature changes affecting both thermostats result in no axial movement, said thermostats having between them a second torsional abutment comprising normally spaced apart switch contacts, manual means for driving one torsional abutment against the other while tensioning both thermostats, a latch for maintaining the tensioned condition in the thermostats and a closed condition of the switch contacts, means for heating one of the thermostats at a different rate than the other whereby movement is effected at the axial abutment, said latch being releasable upon said last-named movement of the axial abutment to permit opening of the torsional abutment, said latch being releasable again only upon abnormal differential heating but not being releasable upon axial movement due to normal differential heating.

8. A thermostat comprising a base, a rotary adjustment shaft on the base, helical thermostatic elements wound around said shaft and abutting one another axially between points on the base, said elements also abutting one another torsionally, the torsional abutment constituting contacts normally open when said thermostatic elements are unstressed, a connection between said shaft and one thermostatic element to stress said thermostatic element and to close said contacts to stress the other thermostatic element when the shaft is moved, means for locally heating one thermostatic element whereby it expands to move the axial abutment, a latch for maintaining said contacts together under normal local heating of the locally heated thermostat but to release the torsional tension under abnormal heating, said latch again becoming potentially operative only after a cooling of the locally heated thermostat to substantially the conditions encountered under said normal local heating.

9. A thermostat comprising a manually rotary shaft, a spring tensioned by rotation of the shaft, a releasable latch for maintaining the rotated and tensioned condition, an axially movable abutment on the shaft and keyed thereto by a key, a switch arm rotary on the shaft, and a helical thermostat between said abutment and the switch arm adapted to expand axially to remove said abutment from said key against the spring upon temperature change in the thermostatic element, the thermostat being under rotary control of the spring to open the switch after said removal.

10. A thermostat comprising a frame, a manually rotary shaft, a spring torsionally tensioned by rotation of the shaft, a latch for maintaining the tensioned condition, manual means for releasing the latch, an axially movable abutment on the shaft and keyed thereto so as to permit said axial movement, a switch arm rotary on the shaft, and a helical thermostat between said abutment and the switch arm adapted to expand axially to remove said abutment from its keyed connection under excessive temperature change in the thermostatic element, and a connection

between said tensioned spring and the abutment whereby the abutment is torsionally moved by the spring after release to open said switch by the rotary connection between the abutment and the switch through said helical thermostat.

11. A thermostat comprising a frame, a manually rotary shaft, a spring torsionally tensioned by rotation of the shaft, a latch for maintaining the tensioned condition, manual means for releasing the latch, an axially movable abutment on the shaft and keyed thereto so as to permit said axial movement, a switch arm rotary on the shaft, and a helical thermostat between said abutment and the switch arm adapted to expand axially to remove said abutment from its keyed connection under excessive temperature change in the thermostatic element, and a connection between said tensioned spring and the abutment whereby the abutment is torsionally moved by the spring after release to open said switch by the rotary connection between the abutment and the switch through said helical thermostat, said frame having a signal opening and means behind the opening indicating switch open position when the manual latch has been released, and means therebehind indicating switch closed position, said last-named means comprising an arm attached to the switch arm and positioned behind said opening when the switch is closed.

12. A thermostat comprising a manually rotary shaft, a spring tensioned by rotation of the shaft, a releasable latch for maintaining the rotated and tensioned condition, an axially movable abutment on the shaft and keyed thereto by a key, a switch arm rotary on the shaft, and two helical thermostats, one of said thermostats expanding and the other contracting upon increase in temperature, said one thermostat being adapted to expand axially to remove said abutment from said key against the spring upon temperature increase in said one thermostat, the removal of said abutment permitting the spring to open the switch.

13. A thermostat comprising a helical coil composed of a strip of composite metal which is thermally responsive axially, stationary contacts, contacts operable by rotary movement with said coil to open and close an electrical circuit through the contacts, the rotary movement of the opening and closing of said contacts taking place at right angles to the direction of the thermally responsive motion of said coil.

14. A thermostat comprising a coil of composite metal wound in the form of a spring, said coil having axial movement in response to temperature change, a stationary contact, a contact rotary with said coil and cooperating with said stationary contact to open and close an electric circuit, means for torsionally stressing said coil, and latching means, said latching means being operable by said axial movement of said coil, and said contacts being operable by said torsional stress in said coil.

15. A thermostat consisting of a thermostatic element comprising a strip of composite metal extending progressively about a minor axis to form minor coils, said minor axis being in turn extended about a second major axis to form major coils, a stop, a member mounted for predetermined motion in response to torsion of said thermostatic element about said major axis and against said stop, means for mechanically twisting the thermostatic element about the major axis to move said member against said stop and to introduce strain into the thermostatic

element to hold said member fixed, a latch adapted to close to maintain said strain after completion of said twisting and responsive to open upon axial movement of the major coils relatively to one another to release strain in the thermostatic element whereby said member may move from its fixed position.

16. A thermostat consisting of a thermostatic element comprising a strip of composite metal extending progressively about a first minor axis to form minor coils, said minor axis being in turn extended about a second major axis to form major coils, a fixed contact and a movable contact mounted for motion of the latter toward former in response to rotation of said thermostatic element about said major axis, means for winding the thermostatic element about the major axis to move said contact and introduce strain into the thermostatic element, a latch closing to maintain said strain after winding and responsive to axial movement of the major coils relatively to one another to open to release strain in the thermostatic element whereby the movable contact may move away from the fixed contact.

17. A thermostat consisting of a thermostatic element comprising a strip of composite metal extending progressively about a minor axis to form minor coils, said minor axis being in turn extended about a second major axis to form major coils, means for placing said major coils under torsional stress, and means actuated by the axial movement of said thermostatic element in response to temperature change, and coacting with said first-named means whereby said torsional stress is relieved.

18. A thermostat consisting of a thermostatic element comprising a strip of composite metal extending progressively about a minor axis to form minor coils, said minor axis being in turn extended about a second major axis to form major coils, means for placing said major coils under torsional stress by applying torsional strain, means coacting with said first-named means to maintain said stress at certain lower temperatures and releasing said stress in response to axial movement of the thermostatic element at certain higher temperatures.
